Harry R. Williams
Atty.

UNITED STATES PATENT OFFICE.

ECTOR F. MARCEAU, OF EAST HARTFORD, CONNECTICUT.

INK AGITATOR.

Application filed April 23, 1925. Serial No. 25,899.

To all whom it may concern:

Be it known that I, ECTOR F. MARCEAU, a citizen of the United States, residing at East Hartford, in the county of Hartford 5 and State of Connecticut, have invented a new and useful Improvement in Ink Agitators, of which the following is a specification.

This invention relates to those devices 10 which are adapted to be applied to printing presses for keeping the roll in the ink fountain supplied with the desired quantity of ink, of the class illustrated and described in Patent #1,379,353 issued to me May 24, 15 1921.

The object of the present improvement is to simplify the construction and provide a cheap and efficient appliance which can be 20 readily attached to the frames of the common forms of printing presses adjacent to the ink fountains, and which has means that will travel continuously back and forth and uniformly distribute thick ink in the required quantity to the desired area on the 25 inking roll that is mounted in the ink fountain, when the press is running.

In the accompanying drawings Fig. 1 shows a plan of an ink distributing appliance which embodies the invention, the ink 30 fountain and roll being well known by those employed in the art are not illustrated. Fig. 2 shows an elevation of the apparatus. Fig. 3 shows a vertical section on the plane indicated by the dotted line 3—3 on Fig. 2 35 looking in the direction of the arrows.

The appliance illustrated has a pair of clamp plates 1 that are designed to be fitted on and fastened by screws 2 to the walls of the press with which the device is to be used. 40 Attached to the front of the clamp plates are angular brackets 3 which support the ends of a pair of parallel guide rods 4. Free to rotate on a stud 5 on the front of one of the brackets is a wheel 6, which may 45 be a pulley or sprocket. Turning in the other bracket is an arbor 7. Attached to the front end of this arbor is a wheel 8, which may be a pulley or sprocket, and attached to the rear end of the arbor is a 50 bevel gear 9. Meshing with this gear is a bevel gear 10 attached to the end of a shaft 11 that is rotatably supported by an extension 12 from the bracket. The outer end of the shaft has a pulley 13 that may be belt- 55 ed to any convenient rotatable part of the

press. An endless belt or chain 14 passes around and connects the driving wheel 8 with the idler wheel 6. When the pulley and shaft are rotated the gears drive the wheel 8 and cause the belt or chain to travel 60 around the wheels in the direction indicated by the arrow 15. Fig. 2.

Loosely mounted so as to slide on the parallel guide rods that are supported by the brackets is a carriage 16, the upper and 65 lower edges of which are grooved to fit the rods. On the front face of this carriage are studs 17 and 18, turning freely on the former of which is a pulley or sprocket wheel 19 and on the latter of which is a 70 pulley or sprocket wheel 20. The wheel 19 is arranged to engage with the under side of the upper length of the belt or chain that passes around the wheels 6 and 8, while the wheel 18 is arranged to engage with the upper side of the lower length of the belt or chain. Guide posts 21 are preferably attached to the carriage so as to hold the belt or chain in engagement with the wheels 19 and 20. Projecting backward from the 75 wheel 19 is a stud 22 and projecting backward from the wheel 20 is a stud 23.

Movable horizontally in the carriage back of the wheels 19 and 20 is a slide 24 which has a forwardly extending portion 25 that 80 is adapted, depending upon the position of the slide, to extend into the paths of revolution of the studs 22 and 23. Adjustably mounted on the guiding rods are stop pieces 85 26. These stops are clamped in the positions to which they are adjusted by thumb screws 27. The ends of the slide 24 extend beyond the ends of the carriage and the projection 25 from the slide is of such a length that when it is in the path of one of the 90 studs 22 or 23 the other stud is free to revolve.

The parts are illustrated in such relation that the stud 22 is engaged by the extension 25 of the slide 24. This prevents the wheel 19 from rotating. Under these conditions, as the wheel 19 is locked and cannot rotate the chain moves the carriage toward the left. During this movement the wheel 20 rotates idly. The carriage travels in this 100 direction until the slide 24 engages the stop 26 and the slide is pushed relatively to the carriage to the right. This action moves the slide extension 25 out of the path of the stud 22 and into the path of the stud 23, 110

releasing the wheel 19 and locking the wheel 20 against rotation. Then the carriage is moved by the chain to the right, until the end of the slide 24 engages the other stop 26 and is pushed back to the position illustrated in Fig. 2, and causes the travel of the carriage to be reversed. The path of travel of the carriage is determined by the location of the stops on the guiding rods. At the back of the carriage is a bracket 28 to which, by a thumb screw 29 any suitable form of agitator blade 30, may be attached. With this construction the carriage is caused to travel back and forth continuously when the press is running so that the agitator will keep the ink in the desired condition.

The invention claimed is:—

1. An ink agitator comprising means for attaching the appliance to a printing press, 20 guiding means supported by the attaching means, a carriage movable back and forth on the guiding means, said carriage being adapted to support an agitator blade, wheels mounted on the attaching means, an endless belt connecting said wheels, mechanism for rotating one of said wheels, wheels rotatably mounted on the carriage, one of which is engaged by one length of the belt and the other of which is engaged by the other 25 length of the belt, means movably mounted on the carriage and adapted to intermittently release one of said carriage wheels, and lock the other of said carriage wheels, and stops adapted to engage and change the 30 position of said movable means with relation to the carriage wheels at the predetermined limits of travel of the carriage.
2. An ink agitator comprising means for attaching the appliance to a printing press, 40 parallel guiding rods supported by the attaching means, a carriage movable back and forth on said rods, said carriage being adapted to support an agitator blade, wheels mounted on the attaching means, an endless belt connecting said wheels, mechanism for 45 rotating one of said wheels, wheels rotatably mounted on the carriage, one of which is engaged by one length of the belt and the other of which is engaged by the other length of the belt, means movably mounted on the carriage and adapted to intermittently release one of said carriage wheels, and lock the other of said carriage wheels, and stops adapted to engage and change the 50 position of said movable means with relation to the carriage wheels at the predetermined limits of travel of the carriage.
3. An ink agitator comprising means for attaching the appliance to a printing press, 55 guiding means supported by the attaching means, a carriage movable back and forth on the guiding means, said carriage being adapted to support an agitator blade, wheels mounted on the attaching means, an endless belt connecting said wheels, mechanism for rotating one of said wheels, wheels rotatably mounted on the carriage, one of which is engaged by one length of the belt and the other of which is engaged by the other length of the belt, a slide movable on the carriage and adapted to prevent the rotation of one of said carriage wheels and allow the rotation of the other of said carriage wheels, and stops adapted to change the relation of the slide to the carriage wheels at the limits of travel of the carriage.

tion to the carriage wheels at the predetermined limits of travel of the carriage.

3. An ink agitator comprising means for attaching the appliance to a printing press, 60 guiding means supported by the attaching means, a carriage movable back and forth on the guiding means, said carriage being adapted to support an agitator blade, wheels mounted on the attaching means, an endless belt connecting said wheels, mechanism for rotating one of said wheels, wheels rotatably mounted on the carriage, one of which is engaged by one length of the belt and the other of which is engaged by the other length of the belt, a slide movable on the carriage and adapted to prevent the rotation of one of said carriage wheels and allow the rotation of the other of said carriage wheels, and stops adapted to change the relation of the slide to the carriage wheels at the limits of travel of the carriage.

4. An ink agitator comprising clamp plates, guide rods supported by the clamp plates, a carriage movable on the guide rods, an endless belt mounted on the clamp plates, 80 mechanism for causing the belt to travel in one direction, wheels rotatably mounted on the carriage and engaged with said belt, a slide movably mounted on the carriage and adapted to lock the wheels to the carriage, 85 and stops adjustably mounted on the guide rods and adapted to engage the slide at the limits of travel of the carriage and cause the slide to alternately lock one wheel and unlock the other wheel.

5. An ink agitator comprising clamp plates for attaching the appliance to a printing press, guide rods attached to the clamp plates, a carriage movable back and forth on the guide rods, sprocket wheels mounted 95 on the clamp plates, an endless link belt passing around said wheels, mechanism for rotating one of said wheels, sprocket wheels rotatably mounted on the carriage, one of which is engaged by one length of the belt and the other of which is engaged by the other length of the belt, a slide on the carriage, 100 said slide having an extension that is adapted to intermittently and alternately prevent and permit the rotation of the carriage wheels, and stops engaged by said slide and adapted to change its position with relation to the carriage wheels at the limits of travel of the carriage.

ECTOR F. MARCEAU.
